UNITED STATES PATENT OFFICE.

JOHANNES TH. PEDERSEN, OF NEW YORK, N. Y.

LUBRICATOR.

No. 804,033.

Specification of Letters Patent.

Patented Nov. 7, 1905.

Application filed December 3, 1904. Serial No. 235,296.

To all whom it may concern:

Be it known that I, JOHANNES TH. PEDERSEN, a citizen of the United States, residing at Woodside, in the county of Kings, city and 5 State of New York, have invented an Improvement in Lubricators, of which the following is a specification.

My invention relates to an oiling device of the visible-feed type adapted for use on machinery generally, and especially adapted and designed for automatic operation or working in connection with the exhaust-pressure from an engine or crank-case, particularly the engine and crank-case of an automobile. My 15 improved lubricator or oiler is also by its particular construction equally well adapted for employment in connection with other different systems of lubrication, and the same may, if desired, be employed for the easy or 20 quick oiling of machinery before the same is started, the automatic operation coming in evidence thereafter.

The object of my invention is to form a device of the simplest and most efficient type.

25 In carrying out my invention I provide a suitable case or receptacle for the oil and regulatable means for admitting the same to said case. A pipe enters the receptacle and is adapted for connection to the exhaust-pressure 30 of an engine or to air under pressure which enters the receptacle from any suitable source, and this pipe at its upper end is preferably provided with a gravity-valve. A glass is provided for observing the height of 35 the oil in the receptacle. Glasses are also provided for noting the visual feed. A device is provided for the quick release of too great a pressure. One or a series of pipes rises within the receptacle, passing through the bottom 40 of the same, and within said pipes are needle-valves having seats in the base of the said receptacle and means for providing for the longitudinal movement of the said needle-valves to either seat or unseat the same in closing 45 off the supply of oil or to regulate the extent of flow, and in connection with the device of my improvement I provide means so admitting the oil and controlling the supply of the same as to provide for an automatic starting 50 and stopping pressure-feed, for gravity and pressure feed, and for gravity-feed alone. My improved lubricator or oiler can also be employed in connection with a tank and pump system.

55 In the drawings, Figure 1 is a vertical longitudinal section and partial elevation repre-

senting my improved apparatus. Fig. 1^a is a cross-section through the sleeve and inverted plan of the loose valve of Fig. 1. Fig. 2 is an end elevation. Figs. 3 and 4 are elevations at opposite sides representing details of the feeding mechanism. Fig. 5 is a vertical section and partial elevation, showing a modified form of the invention. Fig. 6 is a sectional plan at the dotted line *xx* of Fig. 1, 60 and in larger size for clearness. Fig. 7 is a vertical section through a case and devices of a modified form, and Fig. 8 is a partial vertical section and elevation of the central part shown in Fig. 7 and in the opposite position 70 to said parts.

The case *a* is preferably of rectangular form and of cast metal and is provided with lugs *a'* for securing the same to a suitable support or foundation. The front of the case is advantageously provided with a curved wall forming a recess and containing a sight-glass tube *a'*, passing through the same and through the walls of the recess at the respective ends thereof and communicating with the interior of the 80 case or receptacle *a*, in which the height of the oil may be visually noted. The case is provided with a cover *b*, having a depending grooved edge for an intervening packing, the cover setting down upon the upper edge of the 85 case and being secured thereto by tap-bolts 2. The case *a* centrally and along the bottom of the same is provided with a base-rib *a'*, perforated to produce an oil-channel 3, extending from which rib *a'* is a tubular central projection *a'*. The said oil-channel 3 is closed at the ends of the case by screw-plugs 4, and the projection *a'* may be integral with or separate from the rib *a'*.

The cover *b* is formed with a cylindrical 95 flange *b'*, within which and integral with the same and cover are radial arms and a central hub *b'*. The central hub is bored and internally threaded to receive the exteriorly-threaded neck *c'* of the knurled cap *c*. This 100 neck *c'* is hollow. The lower end is perforated and provided with a valve-seat, and a stem 5, having enlarged ends, passes clear through the neck *c'* and knurled cap *c*, the enlarged lower end of the said stem forming a valve against 105 the seat at the lower end of the neck and the enlarged upper end of the stem projecting above the surface of the knurled cap to be pressed and forced down by the application of the finger. Surrounding the stem 5 and 110 within this neck *c'* is a helical spring 6, the function of which is to keep the enlarged lower

end of the stem as a valve seated against the under surface of the neck.

The knurled cap *c* is provided with a radial opening 7, which bisects, or, in other words, 5 communicates with the hollow interior of the neck *c'*. The exteriorly-threaded portion of the neck *c'* fits into the hub *b*², and a washer intervenes between the upper edge of the flange *b'* and the under surface of the cap *c* 10 when the parts are screwed down tightly to place. From the foregoing explanation it will be appreciated that when the stem 5 is pushed downward by the finger against the action of the spring 6 and the lower enlarged 15 end of the stem unseated any pressure of air or gases within the case in excess of atmospheric pressure will then pass out through the hollow neck and through the radial communicating opening 7 to relieve the pressure 20 within the case, as may be desired.

A pipe *d*, provided with a lower tubular portion *d'*, passes through the bottom of the case at one side of the rib *a*³, and the same is secured to the bottom of the case, the pipe *d* 25 rising within the case and being provided at its upper end with a valve 8, which seats against the upper end of the pipe. Connected with the lower end of the tubular portion *d'* is a coupling *d*², to which the end of a pipe 30 is to be connected, extending from a suitable source of exhaust or fluid under pressure which rises through the pipe *d* into the case.

Each sight-feed structure comprises a tubular body *e* with opposite apertures interiorly 35 threaded at its lower end receiving a tube-section of glass 9, held in place by the sleeve *h*, which screws into the lower end of the tubular portion *e*, holding in place the glass section 9, there being preferably washers at 40 the respective ends of the said glass section to produce a tight joint. The upper end of the tubular body *e* is provided with a tapering neck *e'*, which passes into and through the base-rib *a*³ and bottom of the case. This 45 taper neck *e'* is provided with an opening to match or agree with the aperture 3 in the said base-rib, the upper end of the taper neck being provided with a screw-thread for a nut 10, which serves to hold the tubular body *e* 50 and taper neck *e'* firmly to the case and its base-rib, the tapering fit of the parts effecting a liquid-tight joint, obviating the necessity of a packing.

A pipe *f* is secured in the upper portion of 55 the taper neck, and when the parts are in position this pipe passes through the case or receptacle *a* and at its upper end is secured to a sleeve 11, which forms a substantial continuation of said pipe, the said sleeve being exteriorly threaded and passing through the cover *b* and receiving thereon a nut 12, closing 60 the aperture in the cover and tightly holding the pipe in position.

The tubular body *e* is centrally and axially 65 provided with a nipple *e*², which extends down

into the tubular portion, where the lower end is visible at the section-glass 9, and at the upper end of the opening passing through said nipple, and at the intersection of the same with the opening through the taper neck 70 which agrees with the aperture 3 there is a seat for a needle-valve *f'*. This needle-valve or pointed rod fits the pipe *f*, passes through the same and through the opening in the tubular neck that agrees with the oil-channel 3, 75 and at the upper end of the said nipple-valve means are provided for raising and lowering the same so as to bring the same to its seat at the upper end of the tubular body *e* or to raise the same above said seat. Alternate 80 forms of such means are shown in Fig. 1. One means consists of a screw-cap *f*² interiorly threaded to screw upon the upper end of the sleeve 11, the said screw-cap being pinned to the upper end of the needle-valve, 85 so as to rotate the needle-valve with the rotation of the screw-cap. In the structure just described I prefer to form a packing-gland at the upper end of the needle-valve and upper end of the sleeve 11. The other means 90 for raising and lowering the needle-valve comprise a screw-cap *f*³, centrally perforated for a prolongation of the needle-valve which extends through the same. This screw-cap *f*³, like the screw-cap *f*², is received on the upper 95 end of the threaded sleeve 11, and a lever-arm *g* is connected at the pivot 13 thereto to the prolongation of the needle-valve *f'*, and a spring *g'* is provided within the screw-cap *f*³ around the upper end of the needle-valve *f'*, one end of 100 which spring is hooked to a pin of the needle-valve, (shown in Fig. 1,) and the other end bears against the under surface of the screw-cap. In the position of the lever-arm *g*, Fig. 1, in line with the needle-valve, the same is raised 105 off its seat at the upper end of the tubular body *e*. When, however, the said lever-arm *g* is turned down into a horizontal position, the pressure of the spring *g'* will cause the said needle-valve to come tightly against its 110 seat and close the aperture, passing through the nipple of the tubular body.

The sleeve *h*, whose upper end is exteriorly threaded and received into the lower end of the tubular body *e*, is internally shouldered 115 at two places, the upper shoulder forming a seat for an internal ring *h'* and the lower shoulder forming a seat for a loose valve *h*², said loose valve having a stem guided in the ring *h'* and being forked or transversely cut 120 through at its lower end, so as not to close off the opening from the sleeve *h* into the pipe end 15. This pipe end 15 is connected to the lower exteriorly-threaded end of the sleeve by a coupling 14. The lower end of the internal ring *h'* is tapered to form a seat, and the shoulder of the valve *h*² is likewise tapered, and this loose valve is free to rise and fall under pressure, as hereinafter described. When in its elevated position, however, it 125

closes off the opening between the pipe end 15 and the tubular body *e*.

The tubular projection or prolongation *a*⁴ from the rib *a*³ is interiorly threaded, and connected thereto is a tubular body *i*, having a valve or cock *i*', and to the lower end of this tubular body *i* is connected a pipe end 15 and coupling 14 similar to the parts hereinbefore described. This latter pipe end, however, is to be connected to a pipe from a source of lubricating oil or fluid, while all of the other pipe ends 15 are to be connected to pipes for conveying the lubricating fluid or oil to different parts of the machinery for their lubrication, the said cock or valve *i*' being useful for closing off or opening up communication through the tubular body *i*. At the upper end of the tubular body *i* there is provided a seat for the ball-valve 16, which is free to move in a chamber of appreciable area formed in the said tubular projection *a*⁴.

I provide a pipe *k*, an exteriorly-threaded sleeve *k*', and nut *k*², the sleeve *k*', nut *k*², and pipe *k* being substantially an integral structure. The lower end of the sleeve *k*' is provided with integral projections *k*³ spaced apart, and while the portion of the sleeve *k*' below the nut *k*² is exteriorly threaded the portion of the sleeve *k*' above the nut *k*² and where the same surrounds the pipe *k* is tapering and provided at one side with a depression or recess 17 and at the opposite side with an opening 18, which passes clear through both the pipe and the sleeve. The lower threaded portion 35 of the sleeve is provided with an opening 19, and this sleeve *k*' passes through a threaded opening in the bottom of the case or receptacle and also through the bottom of the rib *a*³, the projections *k*³ passing into the chamber at 40 the upper end of the tubular projection *a*⁴, said projections *k*³ coming directly above the ball-valve 16 (see Fig. 1) and limiting the upward movement of said ball-valve when raised from its seat at the upper end of the tubular body *i*. The location of these parts is advantageously central of the case or receptacle, and in view of the manner of connecting said parts to the case or receptacle the pipe *k* consequently rises within the said receptacle 45 and it extends to near the cover thereof. Surrounding the pipe *k* is a pipe *l*, which at its lower end is interiorly tapered to fit around the tapering upper end or inclined seat *k*⁴, the lower end of the pipe *l* having an opening *l*³, coinciding with the opening 18 and the base 50 of the recess 17. A sleeve *m*, having a lower contracted portion exteriorly threaded, is adapted to pass through an opening in the cover *b*, which is interiorly threaded to receive the same, and the taper end of the pipe *l* passes up into the sleeve *m*. The upper end of the sleeve *m* is interiorly threaded to receive a sleeve-nut *m*', between which parts there is formed a gland for a packing.

55 The stem *l*' passes through the sleeve-nut

m' to a joint with the upper end of the pipe *l*, so made that said stem *l*' and pipe *l* turn together. At the upper end of the stem *l*' I provide a thumb-plate *l*², secured thereto in any desired manner, on one face of which thumb-plate is marked the word "Pressure," while on the other face the word "Gravity" is preferably marked. Within the pipe *l* and above the upper end of the pipe *k* I prefer to employ a gravity-disk 20, which closely fits the pipe *l*, is provided with a small central perforation and an upper recessed face.

Figs. 3 and 4 are elevations from opposite sides of the sleeve *k*' and the parts associated therewith. In Figs. 1 and 5 are shown in vertical section the relations of the said parts with the pipe *l*, from Fig. 1 of which it will be noticed that the opening *l*³ coincides with the recess 17 and that the opening 18 on the opposite side is closed off by the pipe *l*, while in the view Fig. 5 it will be noticed that the opening 18 and the opening *l*³ coincide and that the imperforate side of the pipe *l* covers or extends around the recess 17, the illustration Fig. 1 therefore providing a passage-way for the oil or lubricating fluid within the case or receptacle *a* through the opening *l*³, up between the pipes *k* and *l*, over the top of the pipe *k*, and down the same into the oil-channel 3, and from the oil-channel 3 by the central perforation of any tubular body, where the needle-valve is raised through said tubular body, where the dropping oil can be visually noted, past the valve *h*², and away by the pipe end 15. From the view Fig. 5 it will be apparent that the oil in the case or receptacle *a* may pass directly through the coinciding openings *l*³ and 18 into the interior of the pipe *k* down into the oil-channel 3 for like use.

The receptacle or case *a* is preferably filled with oil or lubricating material from a supply-tank by a gravity-flow or from a pump under pressure, the oil entering through the tubular body *i*, past the ball-valve 16, and through the chamber in which the same may pass into the oil-channel 3, up the pipe *k*, through the coinciding openings 18 and *l*³, as shown in Fig. 5, into the case or receptacle until the same is filled to the desired extent, as will appear from the oil in the sight-glass *a*². The seating of the ball-valve 16 or the closing off of the valve or cock *i*', or both, will prevent such oil returning in the same direction. If the parts are now left in this position, the oil in the receptacle or case *a* will flow simply by gravity from said case or receptacle through the coinciding openings *l*³ and 18 down into the channel 3 and therefrom to different parts of the machinery through the tubular body *e* and the parts connected therewith. This position may be advantageous in fully oiling the different parts of the machinery before the same is started and before any pressure from the engine or exhaust is in evidence. To the operator this position is apparent by the word

"Gravity" appearing on the face of the thumb-plate l^2 next to him. When the pressure from the exhaust, engine, or other source enters by the pipe d into the case above the oil therein and its effect is in evidence, the pipe l is to be turned from the position of the parts Fig. 5 to the position of the parts Fig. 1, in which the oil will pass by the opening l^3 up between the pipes l and k and over the top of the pipe k and down the same into the oil-channel 3. This rising oil contacts with the under surface of the gravity-disk 20, which is of appreciable weight and must lift the same from a seat on the upper end of the pipe k , and this disk 20 is raised in proportion to the pressure, and because of its central opening some oil will pass through into the chamber above the same and between it and the under surface of the stem l' , filling said chamber and producing therein a pressure equal to the pressure in the oil beneath the said gravity-disk, thus preventing the gravity-disk from rising too far and permitting the same, when the pressure is reduced, to seat on the top of the pipe k and the oil above the disk to gradually percolate through the opening in the disk 20 into the pipe k . This is the pressure position of the parts, (indicated by the word "Pressure" on the thumb-plate l^2), as shown in Fig. 1.

Should there be pressure in the case or receptacle a and a gravity-feed be desired with the pressure, the pipe l is to be given a half-turn by the hand upon the thumb-plate l^2 , bringing the parts into the position Fig. 5, where the oil will flow through the aligned openings l^3 and 18. The tank may, if desired, be filled with oil or lubricating material by the removal of the knurled cap c and its neck c' , which provide a passage down the flange b' . When the knurled cap c and neck c' are in the position shown in Fig. 1, the case or receptacle a may be relieved of too great a pressure by depressing the stem 5 by the finger placed on the upper end thereof, which unseats the lower end of the stem and forms a passage-way for the exhaust or other surplus pressure to pass through the hollow neck and through the lateral opening 7 in the cap 5.

In Fig. 5 and below the tubular projection a^4 I have shown that the device may be provided with a sight-feed like the sight-feed structure hereinbefore described and comprising the tubular body e and glass section 9, which is interposed between said tubular projection a^4 and the tubular body i , the valve h^3 similar to the valve h^2 , but reversed, having a seat at the upper end of the tubular body e . The form of invention shown in Figs. 7 and 8 provides an equivalent structure to the sleeve m , stem l' and tubular plate i , stem h' , and the openings l^3 and 18 and the functions performed thereby. In these figures the case or receptacle is provided with a horizontal tubular part a^5 from

one side and merging with the bottom of the case and extending toward the center, bisecting the central portion. This tubular part is preferably provided with concentric collars, the inner one exteriorly threaded and the outer one interiorly threaded for the central outer pipe o and central inner pipe n , which are secured thereto. The inner pipe rises in the case to about the same height as the pipe k . The outer pipe preferably extends through the cover and is terminated by a screw-cap o' thereon and closed by suitable washers within said cap and between the same and the cover. The gravity-disk 20 is also advantageously employed in this construction. Within this tubular part a^5 is a stem l^4 , on the outer end of which is a thumb-plate l^2 . This stem l^4 is provided with a transverse aperture 21, alining in a vertical position with the opening, which communicates with the oil-channel 3 and with the central aperture 25 in the tubular part a^5 . The end of the stem l^4 has a recess 22 and an aperture 24 passing through the same, communicating with the recess and also coinciding in one position with an opening 23 in the tubular part a^5 , communicating with the space between the pipes n and o . The opening communicating through the bottom of the case with the oil-channel 3 is prolonged at one corner as a recess 26.

In the position shown in Fig. 7 the openings 23 and 24 coincide, so that oil in the case or receptacle a under pressure will pass from the case or receptacle and recess 22 through the openings 24 23 into the space between the pipes o and n , over the top of the pipe n , down the same, through the openings 25 and 21 down into the oil-channel 3, whereas if the stem l^4 is given a half-turn, so as to reverse its position, the opening 24 is brought into coincidence with the recess 26 and the opening 23 closed off, as in Fig. 8, in which position, Fig. 8, the oil will flow by gravity from the case through the opening 24, recess 26, into the oil-channel 3.

In the foregoing similar characters of reference are applied to similar parts, and the parts in Figs. 7 and 8 not herein described carry the same characters of reference and perform the same functions as the same parts in the other figures and described in connection therewith.

The loose valve h^2 , hereinbefore described, normally rests upon the lower shoulder of the sleeve h , and its main function is to prevent the gases from the engine blowing back into the glasses and oil-receptacle. It is free to move up and down and it is kept in a more or less constant action through the vibration of the engine. This movement has a beneficial effect because the valve acts like the plunger of a pump on the oil in the pipes tending to force the same forward to and through the bearings.

I claim as my invention—

1. In an oiling device, the combination with a case or receptacle and a sight-feed and a pipe extending from the receptacle to a device to be lubricated, of a loose plunger and seat therefor located between the sight-feed and said pipe, the plunger having a free upward and downward movement adapted in its upward movement to close the oil passage-way 10 and in its downward movement to allow the oil to freely escape.

2. In an oiling device, the combination with a case or receptacle and a sight-feed and a pipe extending therefrom to a device to be lubricated, of an internal ring and loose valve intermediate of said sight-feed and pipe and associated therewith, the internal ring having a seat on its under surface, the loose valve having a stem guided in said ring and a seat 20 adapted to contact with the seat thereof and said valve having its lower end forked and adapted when raised against said seat to close the passage-way from the sight-feed to the pipe and when in its downward position to 25 allow the oil to freely escape.

3. In an oiling device, the combination with a case or receptacle, a sight-feed and a pipe extending therefrom to a device to be lubricated, of a sleeve connected to the sight-feed 30 at one end and to said pipe at the other end and having an opening therein stepped or shouldered at two places, an internal ring fitting said sleeve and seated against one shoulder and having a seat on its under surface, a 35 loose valve having a stem at the upper end moving and guided in said ring, there being an intermediate seat to come against the seat of the ring and a lower forked portion normally resting against the other shoulder of 40 said sleeve and having a free upward and downward movement primarily actuated by the vibration of the engine and adapted to close the opening at the end of its upward movement and when in its downward position 45 to allow the oil to freely escape.

4. In an oiling device, a case or receptacle for the oil, having a base-rib beneath and forming a portion of the bottom of the case having a longitudinal oil-channel, a cover for 50 the case or receptacle and means connected with the case and rib and passing through the bottom of the case and through the rib, whereby the oil or lubricating material in the case passes into the oil-channel and from thence 55 away to the parts to be lubricated.

5. In an oiling device, a case or receptacle for the oil, having a base-rib beneath and forming a portion of the bottom of the case having a longitudinal oil-channel, a cover for the case 60 or receptacle means providing for the entrance of pressure within the said case, other means providing for the entrance of the lubricating material into said case, a series of sight-feed devices having parts passing through the bot- 65 tom of the case and the base-rib and intersect-

ing the said oil-channel and also communicating therewith, whereby the lubricating material is caused to pass into the case and therefrom into said oil-channel and by the same to the sight-feed devices.

6. In an oiling device, a case or receptacle for the oil, having a base-rib beneath and forming a portion of the bottom of the case having a longitudinal oil-channel, a cover for the case or receptacle means providing for the entrance 70 of pressure within the case, other means providing for the entrance of the lubricating material into said case, a series of sight-feed devices having parts passing through the bottom of the case and the base-rib and intersecting 75 the said oil-channel and also communicating therewith whereby the lubricating material is caused to pass into the case and therefrom into said oil-channel and by the same to the sight-feed devices, and a back-pressure-valve device 80 85 associated with each sight-feed device.

7. In an oiling device, a case or receptacle for the oil, having a base-rib beneath and forming a portion of the bottom of the case having a longitudinal oil-channel, a cover for the case 90 or receptacle a series of sight-feed devices each comprising an apertured tubular body and a sight-glass received within the case, a tapering neck to the tubular body passing through apertures provided therefor in the 95 bottom of the case or receptacle and of the base-rib and intersecting the said oil-channel, a nipple extending down centrally within said tubular body in line with the tapering neck, with a seat at the upper end thereof; a pipe 100 connected to the tapering neck and extending up into and through said case or receptacle, a needle-valve within said pipe adapted at its lower end to come against the aforesaid seat and providing for a longitudinal movement of 105 the said needle valve or rod.

8. In an oiling device, a case or receptacle for the oil, having a base-rib beneath and forming a portion of the bottom of the case having a longitudinal oil-channel, a cover for the case 110 or receptacle a series of sight-feed devices each comprising an apertured tubular body and a sight-glass received within the case, a tapering neck to the tubular body passing through apertures provided therefor in the 115 bottom of the case or receptacle and of the base-rib and intersecting the said oil-channel, a nipple extending down centrally within said tubular body in line with the tapering neck with a seat at the upper end thereof; a pipe 120 connected to the tapering neck and extending up into and through said case or receptacle, a needle-valve within said pipe adapted at its lower end to come against the aforesaid seat, and a spring-actuated-lever device providing 125 for the longitudinal movement of the said needle valve or rod.

9. In an oiling device, the combination with the case or receptacle, of a cover therefor having a cylindrical flange formed as a part of the 130

cover, with a hub and radial arms extending across within the same, a knurled cap and hollow neck formed as one, the cap adapted to fit down against the cylindrical flange and the 5 neck to pass through a threaded aperture in said hub, and a valve device in said knurled cap and neck.

10. In an oiling device, the combination with a case or receptacle, of a cover therefor having a cylindrical flange formed as part of the cover, with a hub and radial arms within and extending across said flange, the hub being centrally perforated and interiorly threaded, a knurled cap and hollow neck formed as one 15 and the neck exteriorly threaded to screw into the said hub and the cap to fit down upon the said flange, a washer intervening between the said flange and cap, the cap being provided with a radial aperture 7, a stem passing 20 through the cap and neck with the lower end enlarged to act as a valve against a seat at the lower end of said neck, there being an enlargement at the upper end of said stem, and a spring around the stem within said neck at 25 one end seated against a shoulder of the stem and at the other end against the under surface of the top enlargement, substantially as set forth.

11. In an oiling device, the combination with 30 a case and cover therefor, of means providing for the entrance into the case of lubricating material, means providing for the entrance of fluid under pressure within the case above the lubricating material, devices providing for 35 the discharge of the lubricating material by gravity or by pressure or for shutting off the supply, and an apertured gravity-disk 20 to be moved by the discharge of the lubricating material under pressure and assisting in controlling the same.

12. In an oiling device, a case or receptacle with a base-rib to the case having a central and longitudinal oil-channel and a tubular interiorly-threaded projection α^4 , and a cover 45 therefor a sleeve passing through the bottom of the case or receptacle bisecting the said oil-channel and passing into the base of said rib, a pipe secured to the upper end of said sleeve, there being a tapering portion of the sleeve at 50 the union thereto of said pipe forming an inclined seat, said inclined seat formed with a recess at one side and with an aperture through the opposite side and also through the pipe, a surrounding pipe inclined at its free end interiorly fitting over said inclined seat and having an aperture agreeing in one position with the aforesaid aperture, a stem, and means adapted to be engaged by the hand for turning the stem and said pipe so as to provide for 55 the flow of the lubricating material under pressure and by gravity and for closing the same off entirely.

13. In an oiling device, a case or receptacle with a base-rib to the case having a central

and longitudinal oil-channel and a tubular interiorly-threaded projection α^4 , and a cover therefor, a sleeve passing through the bottom of the case or receptacle bisecting the said oil-channel and passing into the base of said rib, a pipe secured to the upper end of said sleeve, there being a tapering portion of the sleeve at the union thereto of said pipe forming an inclined seat, said inclined seat formed with a recess at one side and with an aperture through the opposite side and also through the pipe, a surrounding pipe inclined at its free end interiorly fitting over said inclined seat and having an aperture agreeing in one position with the aforesaid aperture, a stem, means adapted to be engaged by the hand for turning the stem and said pipe so as to provide for the flow of the lubricating material under pressure and by gravity and for closing the same off entirely, and a gravity-disk within the outer pipe above the upper 85 end of the inner pipe, substantially as set forth.

14. In an oiling device, a case or receptacle with a base-rib to the case having a central and longitudinal oil-channel and a tubular interiorly-threaded projection α^4 , and a cover 90 therefor a sleeve device having an exteriorly-threaded portion with an opening through the same with spaced - apart projections on the lower end, with an under portion and with an inclined seat portion passing through the bottom 95 of the case bisecting the said oil-channel and passing into and through the bottom of the base-rib into the tubular projection, a valve device below the said projections in the tubular projection of the case, a pipe axially of said 100 sleeve fitting within the inclined seat portion, said inclined seat portion having a recess 17 and an aperture 18 through the same and through the pipe, and a pipe l concentric with 105 and extending around the aforesaid pipe having an aperture l^3 and interiorly tapered to fit said inclined seat, whereby, when the aperture l^3 coincides with the recess 17 the lubricating material under pressure may pass up 110 between the concentric pipes and when the aperture l^3 coincides with the aperture 18 the flow of lubricating material is by gravity, and when the aperture l^3 is at either side the opening is entirely closed off.

15. In an oiling device, the combination with 115 a case or receptacle and a sight-feed and a pipe extending from the receptacle to a device to be lubricated, of a sleeve connected to the sight-feed at one end and to said pipe at the other end and having an opening therein 120 stepped or shouldered, an internal ring fitting said sleeve and having a seat on its under surface, a loose valve having a stem at the upper end moving and guided in said ring, an intermediate seat to come against the seat of 125 the ring, and a lower forked portion normally resting against the shoulder of said sleeve and having a free upward and downward move-

ment primarily actuated by the vibration of the engine and adapted to close the opening at the end of its upward movement and when in its downward position to allow the oil to 5 freely escape.

16. In an oiling device, the combination with a case or receptacle, and a pipe extending therefrom to a device to be lubricated, of an internal ring and loose valve intermediate thereof 10 and associated therewith, the internal ring having a seat on its under surface, the loose valve having a stem guided in said ring and a seat adapted to contact with the seat thereof and said valve having its lower end forked and 15 adapted when raised against said seat to close the passage-way from the sight-feed to the pipe and when in its downward position to allow the oil to freely escape.

17. In an oiling device, the combination with 20 a case and cover therefor, of means providing for the entrance into the case of lubricating material, means providing for an entrance of fluid under pressure within the case above the lubricating material, a single valve and devices actuated thereby and providing for the 25 discharge of the lubricating material by gravity or by pressure or for shutting off the supply.

18. In an oiling device, the combination with 30 a case and cover therefor, of means providing for the entrance into the case of lubricating material, means providing for an entrance of fluid under pressure within the case above the lubricating material, a single valve and devices actuated thereby and providing for the 35 discharge of the lubricating material by gravity or by pressure or for shutting off the supply, and devices providing for closing off the

supply of the lubricating material to the case and to prevent the accidental escape thereof. 40

19. In an oiling device, the combination with a case or receptacle, of an apertured sight-feed e , a sleeve h connected thereto and an internal ring h' having a seat on the under side, a loose valve h^2 forked on the lower end and a pipe to 45 the device to be lubricated.

20. In an oiling device, the combination with a case or receptacle, of an apertured sight-feed e , a sleeve h connected thereto and having its aperture shouldered at two places, an internal 50 ring h' having a seat on the under side and resting on the higher one of said shoulders, a loose valve h^2 forked on the lower end and located between the said ring h' and the lowermost shoulder of the said sleeve and normally 55 resting on the lowermost shoulder.

21. In an oiling device, the combination with a case or receptacle, of an apertured sight-feed e , a sleeve h connected thereto and having its aperture shouldered at two places, an internal 60 ring h' having a seat on the under side and resting on the higher one of said shoulders, a loose valve h^2 forked on the lower end and located between the said ring h' and the lowermost shoulder of the said sleeve and normally 65 resting on the lowermost shoulder, a coupling 70 screwing upon the lower end of the sleeve h and a pipe connected by said coupling to said sleeve and extending to the device to be lubricated.

Signed by me this 29th day of November, 1904.

JOHANNES TH. PEDERSEN.
